S. N. FALDER

INKWELL BASE

Filed March 13, 1924

INVENTOR: —

Simon N. Falder,

By Martin P. Smith, Atty.

Patented June 16, 1925.

Des. 67,588

UNITED STATES PATENT OFFICE.

SIMON N. FALDER, OF LOS ANGELES, CALIFORNIA.

DESIGN FOR AN INKWELL BASE.

Application filed March 13, 1924. Serial No. 8,913. Term of patent 14 years.

To all whom it may concern:

Be it known that I, SIMON N. FALDER, a citizen of the United States, residing at Los Angeles, in the county of Los Angeles and State of California, have invented a new, original, and ornamental Design for Inkwell Base, of which the following is a specification, reference being had to the accompanying drawing, forming part thereof.

The figure is a perspective view of an inkwell base showing my new design.

I claim:

The ornamental design for an inkwell base as shown.

SIMON N. FALDER.
